(57) **CLAIM**

The ornamental design for a collapsible garment drying device, as shown in the Figures.

DESCRIPTION

FIG. 1 is an isometric view of the collapsible garment drying device in accordance with a first embodiment in a collapsed configuration;

FIG. 2 is a top view of the collapsible garment drying device illustrated in FIG. 1 in the collapsed configuration;

FIG. 3 is a bottom view of the collapsible garment drying device illustrated in FIG. 1 in the collapsed configuration;

FIG. 4 is a front view of the collapsible garment drying device illustrated in FIG. 1 in the collapsed configuration;

FIG. 5 is a rear view of the collapsible garment drying device illustrated in FIG. 1 in the collapsed configuration;

FIG. 6 is a right side view of the collapsible garment drying device illustrated in FIG. 1 in the collapsed configuration;

FIG. 7 is a left side view of the collapsible garment drying device illustrated in FIG. 1 in the collapsed configuration;

FIG. 8 is an isometric view of the collapsible garment drying device illustrated in FIG. 1 in an expanded configuration;

FIG. 9 is a top view of the collapsible garment drying device illustrated in FIG. 1 in the expanded configuration;

FIG. 10 is a bottom view of the collapsible garment drying device illustrated in FIG. 1 in the expanded configuration;

FIG. 11 is a rear view of the collapsible garment drying device illustrated in FIG. 1 in the expanded configuration;

FIG. 12 is a front view of the collapsible garment drying device illustrated in FIG. 1 in the expanded configuration;

FIG. 13 is a left side view of the collapsible garment drying device illustrated in FIG. 1 in the expanded configuration; and,

FIG. 14 is a right side view of the collapsible garment drying device illustrated in FIG. 1 in the expanded configuration.

The broken lines in the drawings form no part of the design to be patented.

1 Claim, 14 Drawing Sheets
